UNITED STATES PATENT OFFICE.

JOSHUA BRYANT POWERS, OF NEW YORK, N. Y.

MOSQUITO GUARD.

Application filed August 7, 1926. Serial No. 127,882.

The present invention relates to protective leggings, as well as for guard coverings for certain other exposed parts of the body, and has for an object to prevent the effective 5 reach, and puncture of the skin, by the stinging equipment of the mosquito and other insects.

It is also an object of my invention to provide a cheap, cool, efficient, light-weight, and 10 easily applied mosquito guard, bulky enough to prevent effective penetration by the stinger of insects, and yet be free from inconvenience when worn.

In the actual manufacture of my invention 15 it is a further object to use inexpensive paper, such as thin crepe paper, for example, for my cheaper goods, and a parchmentized or otherwise toughened paper for my medium priced goods, and an impregnated cambric 20 for example for my higher class goods, subjecting each variety of fabric to a roughening process in order to secure bulky thickness when a plurality of wraps are employed in the making of my guard.

25 In impregnating my paper or other fabric, I may use an alcohol solution of gum shellac for example with the object of securing and maintaining the roughness of the fabric.

With the above and certain other objects in 30 view, which will become apparent as the description proceeds, my invention consists in the novel parts and combination of parts, all as hereinafter will be more fully described and particularly pointed out in the claims.

35 Referring to the accompanying drawings forming a part of this specification in which like numerals designate like parts in all the views;

Figure 1 shows one of my mosquito guards 40 in the form of a legging applied to a limb.

Figure 2 shows a top or plan view of several wraps of one of my mosquito guard-forming strips.

Figure 3 shows a side view of a partial 45 length, cut away in the center, of one of my mosquito guard-forming strips.

Figure 4 shows an edge view of this same mosquito guard-forming strip.

Figure 5 is a transverse sectional view 50 through one of my mosquito guard-forming strips taken as on the line A B of Figure 3, and looking in the direction of the arrows; and

Figure 6 is an enlarged edge view of one end 55 of one of my mosquito guard-forming strips.

With reference to Figure 1 10—10—10 are

the flat sides or convolutions of one of my mosquito guard-forming strips in the form of a legging applied to the limb of a wearer. The legging is started at the ankle and is 60 wrapped spirally around the leg and made fast at the top through the agency of the reinforcing member 11, which is attached to the end of the strip 10 and is impregnated with an adhesive. This adhesive may be 65 either a compound to be warmed, surgeon plaster fashion, to cause it to adhere, or to be wet, glue fashion, to cause it to adhere.

With reference to Figure 2 10 is the strip material and 11 is the reenforced end applied 70 and adhering to the strip after making a wrap or two.

With reference to Figure 3 10 is my strip material, 12 the roughened or corrugated surface, and 13—13 are distant edges produced 75 in my roughening process.

With reference to Figure 4 10 is the mosquito guard-forming strip in edge view, 11 the reenforced end applied thereto.

With reference to Figure 5 10 is the end 80 view of one of my mosquito guard-forming strips, and 13—13 are the outstanding edges thereof.

With reference to Figure 6, which is an enlarged and sectional end view of one of my 85 strips 10 is the strip, 12 the roughened or corrugated surface, 11 the reenforced end provided with an adhesive.

It will now be appreciated that I may take a single strip or two or more strips of crepe 90 paper, for example, and unite them into a compound strip through the agency of any suitable adhesive, a mucilage, for example, and in this way secure a substantially cellular construction, building up a bulky thickness of paper through which the stinging equipment of the mosquito cannot reach. In the place of using thin crepe paper I may use a little heavier weight paper or a cambric, and after running my previously cut 100 strips between roughening or corrugating rollers, I can unite two or more of them in substantially parallel rows through the agency of adhesive, or I can use them as simple single strips, and reinforce the ends by 105 means of a suitable impregnating glue, and a reinforcing member to be pasted to hold the legging secure on the limb of the wearer.

With my roughened or corrugated strips of fabric, either in single thicknesses or in superimposed or compounded layers it now becomes obvious that I may secure a very cheap, 110

light weight but bulky mosquito guard legging, easily applied, worn, and thrown away after use, but with such thickness as to prevent the stinging equipment of a mosquito or other insect, from penetrating and reaching through effectively to the flesh of the limb protected by my guard.

Having described my invention, I claim:

1. A legging comprising a strip of crepe fabric whose corrugations are treated with a solution to aid in maintaining said corrugations, said strip adapted to create a substantially cellular structure when wrapped about a limb, and provided with means for making fast one of the ends of said strip.
2. A legging comprising a strip of paper whose surface is provided with a plurality of indentations and raised portions, said fabric being treated with a solution to preserve said surface formation; a reinforcement provided on one of the ends of said strip; and an adhesive on said reinforcement.
3. A legging comprising a plurality of associated superimposed strips of fabric each provided with an undulating surface, the edges of the composite fabric being extended beyond the surface thereof; a reinforcement provided on one of the ends of said com-

posite strip; and an adhesive on said reinforcement whereby the composite strip may be wound about a leg and self-secured to provide a protection against the bites of insects, etc.

4. A legging comprising a plurality of associated superimposed strips of indented fabric treated to maintain the indentations, the plurality of strips being united by means of an adhesive, and means to secure the composite fabric strip to a leg including an adhesive applied to one end of said strip.

5. A legging comprising a composite of a plurality of associated superimposed strips of paper each having a surface provided with undulations extending in plural directions and treated with a solution to preserve said undulations, the edges of the composite extending beyond the surface thereof to reinforce the same; a separate reinforcement provided on one of the ends of said composite; and an adhesive on said last named reinforcement.

Signed at New York city, in the county of New York and State of New York, this 5th day of August A. D. 1926.

JOSHUA BRYANT POWERS.
